UNITED STATES PATENT OFFICE.

JOHN MABUS AND FRANK L. HAY, OF LILLY, ILLINOIS.

CORN OR GRAIN DUMP AND ELEVATOR.

SPECIFICATION forming part of Letters Patent No. 698,528, dated April 29, 1902.

Application filed March 7, 1901. Serial No. 50,191. (No model.)

To all whom it may concern:

Be it known that we, JOHN MABUS and FRANK L. HAY, citizens of the United States, and residents of Lilly, in the county of Tazewell and State of Illinois, have invented a new and Improved Corn or Grain Dump and Elevator, of which the following is a full, clear, and exact description.

The object of the invention is to provide a machine in which a vehicle containing a load may be driven thereupon and the load dumped and distributed in suitable or desired quantities.

A further object of the invention is to provide a machine of the character indicated which is compact, simple, and cheap.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a plan view of the machine. Fig. 2 is a rear elevation of the machine. Fig. 3 is a side elevation of the machine. Fig. 4 is a vertical section taken practically on the line 4 4 of Fig. 1. Fig. 5 is a longitudinal vertical section through the conveyer and a transverse section through the door covering the inlet to the conveyer and a longitudinal section through a slide interposed between the conveyer and the cover. Fig. 6 is a longitudinal vertical section through the machine, showing the dumping-rail for the vehicle in dumping or inclined position, taken on the line 6 6 of Fig. 1. Fig. 7 is a detail perspective view of a link of the chain belt of the conveyer and elevator. Fig. 8 is a side elevation of the connected conveyer and elevator, parts being broken away; and Fig. 9 is a side elevation of the delivery-shoe attached to the elevator, parts of the shoe being broken away.

The base A of the machine consists of a series of longitudinal beams 10, which in addition to their functions as supports likewise constitute runners for the machine, and at the central rear portion of the base a draft device 11 is located. The base is completed by the addition of two wings A' and A'', lo-

cated at opposite sides at the rear portion of the machine, as is shown best in Fig. 1. The frames of the wings A' and A'' consist of transverse bars or beams 13 and longitudinal beams 12; but the transverse beams of the wing A'' are preferably made heavier than those of the opposite wing A', as the wing A'' is adapted to sustain greater weight.

Uprights 14 are located at the front portion of the base A, which uprights rest upon transverse beams 15, crossing the lower beams 10, and are connected at the top by transverse beams 15^a. The front wall or partition of the base is strengthened by suitable braces 16. Between the center of the base and its rear end a series of uprights 17 is located, resting upon transverse beams 18, supported by the base and connected at the top by corresponding transverse beams 18^a, while braces 19 support this intermediate partition or wall. Upper longitudinal beams 20 and 21 rest upon the forward upper transverse beams 15^a and the intermediate beams 18^a, and at a point just forward of the central partition comprising the uprights 17 and the cross-beams 18 and 18^a the upper edges of the upper longitudinal beams 20 and 21 are given a downward and rearward inclination. The rear ends of these beams 20 and 21 rest upon rear transverse beams 23, which are supported by uprights 24, resting on corresponding lower transverse beams 23^a, as shown in Fig. 6.

A platform 25 is secured upon the innermost upper longitudinal beams 20 of the structure, and strips 26 are secured upon the upper face of the outer upper beams 20, the strips being of equal length with the platform. The platform 25 and strips 26 extend from the forward ends of the upper longitudinal beams 20 to that point where the inclination 22 commences.

Socket-plates 27 are suitably secured upon the upper face of the side strips 26 and the upper face of the platform 25, the said socket-plates being located at the central portion of these parts, as is illustrated in Fig. 1. A shoe 29 is located between opposing socket-plates 27, and these shoes are inclined from their ends in direction of the center and are provided with side flanges at their central portions, as shown in Figs. 1 and 2, and each shoe 29 is provided with trunnions 28, adapt-

ed to enter suitable recesses in the socket-
plates 27. These shoes are secured in any
suitable or approved manner to the upper
faces of the tracks or dumping-bars 30, and
5 these tracks or dumping-bars 30 fill the spaces
between the longitudinal edges of the plat-
form 25 and the inner edges of the outer strips
26, as shown in Fig. 1. The wheels of a ve-
hicle are adapted to rest upon these dumping-
10 bars or tracks 30, and the shoes 29 are given
the shape described in order that the wheels
of a vehicle may readily pass over them.
When the wheels of the vehicle pass to the
rear of the shoes 29, if the rear ends of the
15 dumping-bars or tracks 30 are not supported
they will drop to the inclined position shown
in Fig. 6 and the load carried by the vehicle
will be dumped.

A derrick 31 is supported upon the wing
20 A² and extends upward therefrom, and this
derrick is provided with a windlass 32, oper-
ated by a suitable crank 33 or its equivalent.
A rope 34 is wound around the windlass 32,
and this rope is passed up over a pulley 35 at
25 the top of the derrick and is adapted for at-
tachment to the upper portion of the eleva-
tor C', to be hereinafter described.

A shaft 36 is journaled in suitable bearings
37, attached to the upper outer longitudinal
30 beams 20 just below the rear edge of the plat-
form 25, the bearings 37 extending downward
below the lower edges of the said beams 20
and of the mating beams 21. This shaft 36 is
provided with crank-arms 38, (shown in Fig.
35 6,) and these crank-arms are adapted to nor-
mally engage in recesses in the rear ends of
the dumping-bars or tracks 30 to normally
hold said bars or tracks in a horizontal pos-
ition. The crank-arms 38 of the shaft 36 are
40 thus held by carrying an arm 39 forwardly
from the central portion of the shaft 36, as
shown in Figs. 3 and 6, and a spring 40 is at-
tached to this arm and to the base A, as is
also shown in said figures. The crank-arms
45 38 of the shaft 36 may be carried out of en-
gagement with the dumping-bars or tracks 30
by locating a crank-arm 41 at one end of the
shaft, which crank-arm extends upward and
is pivotally connected to a rod 42. This rod
50 extends rearward and terminates in a handle
43 at its rear end, and said bar is passed
through a guide 44, usually in the form of a
staple, and secured to the derrick 31, as shown
in Figs. 1, 2, and 3. This rod 42 is provided
55 with a downward projection or pin 45 near its
handle end for a purpose to be hereinafter set
forth.

Fenders 47 in the form of plates are hinged
60 to the upper inner edges of the inner upper
longitudinal beams 21, and these fenders nor-
mally fold outward and rest upon the upper
beams 20 and 21. At the rear end of the plat-
form 25 a downward and rearward inclined
65 wall 46 is constructed, (shown in Fig. 4,) which
rests upon the upper portion of the interme-
diate partition of a frame on the upper cross-
bars 18 of said partition, as is also shown in

Fig. 4. A second platform 48 is hinged at its
rear edge to a cross-bar 50, located upon the
70 rear ends of the upper longitudinal beams 20
and 21, and meets the rear edge of the plat-
form 25, the outer side sections of the said
platform, and the rear ends of the dumping-
75 bars or tracks 30. This hinged platform 48 is
provided upon its inner face with two curved
fingers 49, which fingers are at the rear of the
fenders, and when the hinged platform is
closed the fingers extend down into the spaces
between the longitudinal beams 20 and 21.
When the hinged platform 48 is raised, as
80 shown in Fig. 6, the fingers engaging with the
outer faces of the fenders 47 will raise the
said fenders, and when the load is dumped it
will enter the spaces surrounded by the fenders,
the hinged platform, and the inclined 85
wall 46. When the hinged platform is raised
and the rod 42 is drawn rearward to release
the crank-arms 38 from the dumping-bars 30,
the projection or pin 45 on the said rod 42 is
90 brought in engagement with the stop 48', lo-
cated upon the hinged platform 48, which
stop in the raised position of the platform en-
gages with a member of the derrick 31, as
95 shown in Fig. 6, and as long as the rod 42 is
drawn rearward the hinged platform is held
in its upper position. This hinged platform
may be raised by a lever, but is usually op-
erated by hand.

Tracks 51 are secured upon the inner faces
of the rear uprights 17 and 24, as shown in
100 Fig. 4, and these tracks are adapted to sup-
port a conveyer C. This conveyer C consists
of side pieces 52, having outwardly-flared
longitudinal upper portions 53, and at inter-
vals along the outer faces of the side pieces
105 54 are secured, provided with offsets 55, which rest upon the tracks 51,
as is also shown in Fig. 4. These metal strips
54 are connected at their bottom portions by
metal cross-bars 56, which extend across the
110 bottom of the sides of the said conveyer and
serve to support longitudinal strips 57, also
preferably of metal, and these strips 56 and
57 constitute the bottom portion of the con-
veyer, which is practically open. A hori-
115 zontal partition 58 is located about midway
in the said conveyer, extending from end to
end thereof, and the said conveyer is of suffi-
cient length when placed upon the tracks 51
to extend beyond both sides of the main por-
120 tion of the machine or over the wings A' and
A². The conveyer is open at both of its ends.

A central track 60, preferably of metal, is
secured upon the upper face of the partition
58, as is also shown in Fig. 4, and this track
60 is provided at its side edges with upwardly
and inwardly extending flanges 61, the said
flanges being angular in cross-section, and
narrower tracks 62, also of metal, are located
upon the partition 58 at each side of the
130 central track. The conveyer chain or belt D
travels at both sides of the partition 58, and
the links d of the chain travel above the cen-
tral track 60. These links are provided at

their sides with horizontal lugs 63, and these lugs enter the space between the overhanging portions of the flanges 61 and the bottom portion of the central track 60, as shown in Fig. 4. Under this arrangement the links of the chain belt D are held in proper position in the conveyer.

Sundry of the links D, as is particularly shown in Fig. 7, are provided with vertical lugs 64 at each side, the lugs having apertures 65 therein, and one face of the lugs 64 is made smooth in order that plates 66 may be bolted or otherwise secured to the said lugs, which plates are provided with recesses 67 in their under edges, as shown in Fig. 4, to clear the flanges 61 on the central track 60, as the plates 66 extend over the side tracks 62 and practically from one side of the conveyer to the other. These plates 66 are adapted to engage with material and carry the same forward or upward, as occasion may demand, and the working faces of these plates 66 may be straight or curved, as desired. The belt D is passed over a suitable pulley 68, located at what may be termed the "right-hand" end of the conveyer, and this pulley is mounted on a suitable shaft 69, which extends beyond both sides of the conveyer.

Dust and dirt are prevented from reaching the pulley 68 by hinging a guard 70 in the conveyer at its receiving end, as shown in Fig. 5, and a slide 71 is mounted to travel in the upper or flaring portion of said conveyer to and from that space which is between the inner longitudinal beams 21, as shown also in Fig. 5. The slide 71 is connected by a link 72 with a lever 73, supported usually by a standard 73^a, secured to the upper rear cross-bar 50, as is best shown in Fig. 2. Prior to raising the hinged platform 48 the slide 71 is carried to a position below the space between the inner longitudinal beams 21, so that when a load is dumped it is received upon the slide 71, and the material deposited on the slide may be delivered in desired quantities and at suitable intervals to the conveyer-belt D.

The team is driven up an inclined platform 75, located at the rear end of the main platform 25, and after the load has been dumped the dumping-bars or rails are restored to their locked position, and the hinged platform is closed at the time the team is driven over the hinged platform and down the inclined plane or platform 74 at the front of the machine. These platforms 74 and 75 are held in position by hooks 76 or latches of any description.

The elevator C', heretofore referred to, is identical in construction with the construction of the conveyer C, which has been described, except that the upper end 77 of the elevator is closed and an opening is made in the bottom upper portion of the elevator, which opening is surrounded by a funnel 79. (Shown in Figs. 2 and 9.) This funnel is removably connected with the elevator by

means of bolts 80 and hooks 81 or other approved means, as is also shown in Fig. 9. A sprocket-wheel 82 is located at the top portion 70 of the elevator C', the said sprocket-wheel 82 being secured to a shaft 83, and this shaft carries at one of its ends a sprocket-wheel 84, as shown in Fig. 1. A bail 85 is attached to the upper portion of the elevator, and the 75 rope 34 from the windlass after being passed over the pulley 35 of the derrick is attached to this bail, so that by operating the windlass 32 the elevator may be given more or less of an elevation, as the elevator is pivotally connected at its bottom portion with the right-hand end portion of the conveyer C and with the derrick 31 just above the wing A² of the frame. This pivotal connection may be effected in different ways. For example, 80 bifurcated arms 86 may be attached to the side portions of the conveyer C at its right-hand end, and plates 87 are secured to the lower side portions of the elevator C'. These plates 87 are provided with pins 88, which 85 pass through the members of the bifurcated portions of the plates 86, attached to the conveyer, and find bearings in boxes 89, secured to the derrick, as shown in Fig. 2; but, as illustrated in Fig. 8, plates 90, having pins 90, may be secured to the sides of the conveyer C, and plates 91 are then secured to the side portions of the elevator, which plates 91 have bifurcated lower ends 91^a to receive the said pins 90^a. In Fig. 8 we have illustrated 100 the elevator as provided with a cover 92, attached to the outer side bars 54, and a lower section 93 of the said cover extends over the upper portion of the conveyer C, where the conveyer connects with the elevator. If desired, the elevator and conveyer may be held rigidly at any desired angle one to the other by employing angle or triangular plates 94, 105 adjustably attached to both the conveyer and elevator by means of bolts 95, passed through 110 suitable slots in the plates, as shown in Fig. 8.

A conducting-chute E is detachably attached to the funnel 79, and this conducting-chute preferably comprises an upper section e, made up of a series of pivotally-connected telescopic sections 96, as shown in Fig. 9, and a lower section e', detachably connected to the upper section. The lower section in its turn consists of two tubular members 97 and 98, which are adjustably and telescopically 115 connected by suitable bolts 99, passed through a slot 100 in the outer section 97 and into the inner section 98, as is also shown in Fig. 9.

An endless chain belt which is guided in the conveyer continues up through the elevator, as has been mentioned, and it is very important that different means shall be devised for driving the said continuous belt, as frequently the machine occupies such positions that one drive-shaft might be inaccessible. To that end a number of drive-shafts are employed, all tending to drive the said belt. For example, the shaft 69, which is connected directly with the supporting-pul-

ley for the chain belt at the receiving end of the conveyer C, may have power applied to one of its ends, and at its opposite end a sprocket-wheel 101 is secured, over which a belt 102 is passed, and this belt likewise passes over a sprocket-wheel 103, located on an outer shaft 104, parallel with the shaft 69. The shafts 69 and 104 are journaled in suitable bearings located on the frame of the wing A' on the main frame. The shaft 104 is adapted to receive power at one end, and at its opposite or forward end a bevel-gear 105 is secured. This bevel-gear meshes with a gear 106, located on the shaft 107, adapted to receive power at one end, and this shaft 107 is likewise journaled in suitable bearings in the wing A', but is at right angles to the shafts 69 and 104. Another shaft 108 is journaled in suitable bearings at the rear of the frame, extending from wing to wing. This shaft 108 at that end which has bearings in the wing A' is provided with a bevel-gear 109, and this gear 109 meshes with a similar gear 109^a, located on the rear end of a shaft 110, extending transversely across the wing A' and journaled in suitable bearings carried by said wing. At the forward end of the shaft 110 a sprocket-wheel 111 is secured, connected by a chain-belt 112 with the sprocket-wheel 84 on the shaft 83, which carries the upper sprocket guide-wheel for the endless chain D and which is located at the upper portion of the elevator C', as is best shown in Fig. 1. Under this arrangement it will be observed that no matter what position the machine may occupy ready driving access is secured to the combined conveyer and elevator belt D. A pulley 113 is usually attached to the right-hand end of the shaft 110, and this shaft is usually employed as the main driving-shaft.

The conveyer C is held in position in the machine in any suitable or approved manner—as, for example, hooks 114, attached to a cross-bar 115 at the receiving end of the conveyer, are adapted for engagement with the shaft 104. It will be observed that by constructing a machine as above set forth a vehicle containing a load may be driven upon the machine and the load dumped and distributed as desired to the conveyer, and from the conveyer the material of the load is received by the elevator and discharged at the upper end of the elevator into the conducting chute, which may be of any desired inclination, so as to deliver the material at any point where convenience may demand.

The dump is self-closing, as when the wagon is drawn from the platform the dumping bars or tracks are restored to their normal position and the spring 40 restores the locking device for the dumping bars or tracks to locking position.

Having thus described our invention, we claim as new and desire to secure by Letters Patent—

1. In agricultural machines, a tilting sup-

port, means for locking and releasing the tilting support, and a hinged platform at one end of the tilting support and held in an open position by the said locking and releasing device of the tilting support, as set forth. 70

2. In agricultural machines, a dumping-support, means for locking and releasing the dumping-support, a hinged platform, fenders 75 raised and lowered by the hinged platform, a conveyer located beneath the hinged platform, and an elevator connected with the conveyer.

3. In agricultural machines, a dumping-support, means for locking and releasing the dumping-support, a hinged platform at one end of the dumping-support, fenders raised and lowered by the hinged platform, a conveyer located beneath the hinged platform, an 85 elevator connected with the conveyer, and a slide operating at the receiving portion of the conveyer at a point beneath the hinged platform, for the purpose of regulating the supply of material to the conveyer, as specified. 90

4. In agricultural machines, a hinged platform, a support therefor, fenders arranged to be raised and lowered by the hinged platform, a conveyer beneath the hinged platform, and a slide operating in the conveyer beneath the 95 hinged platform, as specified.

5. In agricultural machines, a hinged platform, a support therefor, fenders hinged to the support, which fenders drop to the support by gravity, fingers secured to the hinged platform, adapted for engagement with the under faces of the fenders to raise the same when the hinged platform is raised, and a conveyer located beneath said platform, as described. 100

6. In agricultural machines, a hinged platform, a support therefor, fenders hinged to the support, and closing upon the support in opposite directions, extensions from the hinged platform, which are arranged to engage with the under faces of the fenders, a conveyer 110 located below the hinged platform, an elevator connected with the conveyer, and a slide mounted in the conveyer, having movement beneath the hinged platform, for the purpose set forth. 115

7. In agricultural machines, a tilting support, arms normally held in locking engagement with the tilting support, means for operating said arms to move them out of engagement with said support, and a hinged platform at one end of the tilting support and engaged by the means for operating the arms for holding the platform raised at the time the arms are disengaged from the tilting support, as set forth. 120

8. In agricultural machines, a fixed platform, dumping bars or rails pivotally carried by the fixed platform, a tension-controlled shaft provided with crank-arms having normal locking and supporting engagement with the dumping-bars, a second platform located adjacent to the dumping-platform, a support to which the second platform is hinged, fenders hinged to said supports and arranged to 130

normally rest flat thereon below the hinged platform, projections from the hinged platform adapted for engagement with the under faces of the fenders to raise the same when 5 the hinged platform is raised, and a conveyer located beneath the hinged platform, for the purpose specified.

9. In agricultural machines, a tilting support, a rock-shaft provided with arms normally held in engagement with said support, a rod connected with said shaft for operating it, and provided with a projection, and a hinged platform at one end of the tilting support and provided with a stop adapted to be 15 engaged by the projection on the operating rod, as and for the purpose set forth.

10. In agricultural machines, a platform, dumping-bars mounted in the platform, a crank-shaft, the crank-arms of which are 20 adapted to engage the ends of the said bars, a spring connected with an arm of the crank-shaft, an operating-rod connected with the crank-shaft and passing through a guide, said rod being provided with a handle at its end 25 and with a projection between its ends, and a hinged platform at one end of the main platform and provided with a stop adapted to be engaged by the projection of the operating-rod, as set forth.

30 11. In agricultural machines, a platform having longitudinal openings therein extending from end to end, socket-plates secured to the platform at opposite sides of the central portions of the said spaces, dumping-bars located in the said spaces, a shoe secured to each dumping-bar, inclining from the center downward to its ends, the central portion of each shoe being provided with flanges at its sides, and trunnions extended from the side portions 35 of the said shoes, and adapted for bearing upon the socket-plates, as and for the purpose set forth.

12. In agricultural machines, a platform having longitudinal openings therein extending 45 from end to end, socket-plates secured to the platform at opposite sides of the central portion of said spaces, dumping-bars located in the said spaces, a shoe secured to each dumping-bar, inclining from the center downward to its ends, the central portion of each 50 shoe being provided with flanges at its sides, trunnions extended from the side portions of the said shoes, being adapted for bearing upon the socket-plates, a crank-shaft located beneath said platform at one end, the crank- 55

arms of which shaft are adapted for locking and supporting engagement with the ends of the dumping-bars, a tension device for the said shaft, and means for turning the said shaft against the resistance of the tension device, as set forth. 60

13. In an agricultural machine, a frame, tracks secured to said frame, a conveyer having extensions from its sides adapted to rest upon the said tracks, a hinged platform located above the conveyer, hinged fenders located between the hinged platform and the conveyer, which fenders are adapted to drop by gravity, and means substantially as described, for raising the said fenders when the 70 hinged platform is elevated, for the purpose described. 65

14. An agricultural machine, comprising a tilting support, a hinged platform at one end of the tilting support, oppositely-arranged 75 fenders hinged to the fixed support carrying the hinged platform and at right angles to the said hinged platform, a conveyer arranged below the hinged platform and at right angles to the tilting support, and an elevator 80 connected with the conveyer, as set forth.

15. An agricultural machine, comprising a tilting support, a hinged platform at one end of the tilting support, hinged fenders at right angles to the hinged platform, a conveyer below the hinged platform, a derrick against which the fenders rest when opened, and an elevator supported by the derrick and connected with the conveyer, as set forth. 85

16. An agricultural machine, comprising a 90 stationary platform, tilting bars mounted in the platform, means for locking and releasing the tilting bars, a hinged platform at one end of the stationary platform, and held open by the tilting bars locking and releasing means, 95 hinged fenders at right angles to the hinged platform and raised and lowered by the hinged platform, a conveyer below the hinged platform, a derrick against which the fenders rest when opened, and an elevator connected with 100 the conveyer and adjustably supported by the derrick, as set forth.

In testimony whereof we have signed our names to this specification in the presence of two subscribing witnesses.

JOHN MABUS.
